SIGNAL RECEIVING SYSTEM

Application filed November 26, 1928. Serial No. 321,831.

This invention relates generally to systems for receiving signal energy of radio or carrier frequency.

It is a general object of this invention to devise a novel resonant network for transferring signals of radio or carrier frequency from a source to detecting or integrating means.

It is a further object of this invention to devise a novel form of network to be used in a signal receiving system for the purpose of amplifying radio energy.

It is a further object of this invention to devise a novel amplifying network of the regenerative type which is comparatively stable in operation and which is particularly useful in receiving signal energy of relatively high frequency and short wave lengths.

Referring to the drawing:

Figure 1 is a circuit diagram illustrating one form of our invention.

Fig. 2 is a circuit diagram illustrating the nature of the network incorporated in the system of Fig. 1.

Fig. 3 illustrates our invention as applied to an antenna cooperatively positioned with respect to wave reflecting means.

Fig. 4 is a circuit diagram illustrating a radio system incorporating cascade amplifying means.

In radio or carrier wave receiving systems utilizing electron relays, it has become conventional practice to provide reactive input and output circuits for the relays which are tuned to the frequency of signal energy to be received. This invention differs from conventional systems in that input and output circuits provided for one or more of the relays are not tuned to the frequency of operation, but are interrelated in such a manner as to form a network resonant as a whole to the frequency of operation.

Referring to the circuit diagram of Fig. 1, the system therein disclosed utilizes a source of signal energy of radio or carrier frequency represented by radio antenna 10. For integrating the signal energy there is shown a detector 11 of the electron relay type, and interposed between the input of this detector

and the antenna 10 there is a network designated generally at 12.

The network 12 in its preferred form utilizes an electron relay 13 of conventional construction, consisting for example of a cathode 14, grid 15 and anode 16, positioned within an evacuated envelope. The input circuit for this relay has been indicated generally at 18 and can be formed by inductance 19 shunted by variable capacitance 21. Two points of different potential on circuit 18 are connected to the grid and cathode of relay 13. For example we have shown a direct conductive connection between grid 15 and one terminal of inductance 19, while the other terminal of inductance 19 is connected to cathode 14 thru a high frequency by-pass condenser 22.

The output circuit for relay 13 is designated generally at 23 and consists of inductance 24 shunted by variable capacitance 26. Two points of different potential on this circuit are connected across the grid and anode of relay 13. For example one terminal of inductance 24 has a direct conductive connection to anode 16, while the other terminal of inductance 24 is connected to grid 15 thru a blocking condenser 27. For applying an operative anode potential to the relay we have shown conventional means such as a B-battery 28, having its negative terminal connected to cathode 14 and its positive terminal connected to anode 16 thru a suitable high frequency choke 29. The cathode of relay 13 is also shown as heated by a source of current conventionally represented by A battery 31.

In practice the input circuit 18 is suitably coupled to a source of signal energy, such as antenna 10, while output circuit 23 is coupled to the input circuit of further radio frequency amplifying means or to the input of detector relay 11. For convenience relay 11 has been shown as being of the conventional type having an input circuit 32 inductively coupled to circuit 23 of amplifying relay 13. The audio frequency output of relay 11 can be reinforced by repeating the same thru audio frequency amplifier 33 and is then impressed upon a suitable translator 34.

In that form of the invention shown in Fig. 1 we have incorporated means for modulating the received signal energy. This can be provided by an electron relay 36 having its grid connected to a suitable source of audio frequency current indicated by oscillator 37. The anode and cathode of this relay are connected across an inductance 38, which in turn is included in the grid-cathode circuit 18. As the potential upon the grid of relay 36 is varied the plate-cathode impedance is likewise varied so as to vary the translating characteristics of network 12.

Since the network 12 is generally operated regeneratively, we preferably provide means whereby the degree of regeneration can be controlled. Such means can be formed by a resistance 39 connected across A battery 31. This resistance has a variable tap 41 connected to the return lead for input circuit 18.

The operation of network 12 can best be explained by reference to the simplified diagram of Fig. 2. It will be noted that the reactive input and output circuits 18 and 23 respectively are intercoupled thru the anode-cathode capacitance of relay 13 indicated at 42. Assuming now that input circuit 18 is negatively reactive and output circuit 23 positively reactive with respect to a desired frequency of operation, these circuits when taken in conjunction with the inter-coupling capacitance 42 form an electrical network which is resonant to a given frequency of operation. For example in a given instance input circuit 18 was adjusted so as to be individually resonant to a frequency of 16,200 kilocycles and output circuit 23 adjusted so as to be individually resonant to a frequency of 18,500 kilocycles, in order to make the network as a whole resonant to a frequency of 17,900 kilocycles. It is apparent that the individual adjustment of circuits 18 and 23 will vary somewhat for relays of different construction and for circuits having different inductance to capacitance ratios. Generally the inductance of circuit 23 is made relatively high compared to its capacitance components, and in fact the capacitance 26 can be reduced to zero. In this event circuit 23 is completed thru the grid anode capacitance of relay 13.

The network as described above is a one-way device and will therefore amplify current variations impressed upon its input. Furthermore with proper adjustment of the potentials placed upon the grid 15 and anode 16, the relay operates regeneratively to secure relatively efficient amplification. In the system of Fig. 1 the degree of regeneration can be controlled by varying the position of tap 41. It has been found that even when the network is operating regeneratively, it is relatively stable and will not readily spill over into local oscillation.

In Fig. 3 we have shown a radio system

similar to that of Fig. 1 except that the antenna is associated with a wave reflector. Thus in this instance the antenna conductor 310 has been positioned at the focal center of a paraboloidal wave reflector 44. Such an arrangement of wave reflector and antenna conductor has been described in our copending application No. 279,244 filed May 21, 1928. As explained in said copending application, the wave length of operation must bear a definite relationship to the focal length of the reflector, as for example the wave length can be four times the focal wave length. The effective length of the antenna conductor should also be about one half the wave length of energy to be received. The resonant network 12 in this case has been modified to the extent that the modulating means has been omitted.

In Fig. 4 we have shown a system utilizing our invention in which two resonant networks 12a and 12b are connected in cascade and are interposed between the source of signal energy and the integrating means. In this case the respective input and output circuits for the networks are tuned in such a manner that each network is resonant to the same frequency of operation.

We claim:

1. A signal receiving system comprising a source of signal energy of radio frequency, an electron relay having grid, cathode and anode electrodes, a reactive input circuit connected across the grid and cathode of said relay and coupled to said source, and a reactive output circuit connected across the grid and anode of said relay, said circuits being oppositely reactive with respect to a given frequency of operation and affording a network resonant as a whole to said frequency of operation in conjunction with said relay.

2. A signal receiving system comprising a source of signal energy of radio frequency, an electron relay having grid, cathode and anode electrodes, a reactive input circuit connected across the grid and cathode of said relay and coupled to said source, and a reactive output circuit connected across the grid and anode of said relay, said input circuit being non-resonant of itself to the frequency of operation but said circuits taken together and in conjunction with the capacitance between the cathode and anode forming a network resonant as a whole to said frequency of operation.

3. The method of receiving signal energy of radio frequency characterized by the use of an electron relay having reactive input and output circuits connected to the same, said method comprising adjusting said circuits so that they are individually non-resonant to the frequency of said signal energy and interrelating said circuits thru said re-

lay whereby a network is formed which is resonant to said frequency.

4. The method of receiving signal energy of radio frequency characterized by the use of an electron relay having reactive input and output circuits connected to the same, said method comprising adjusting said circuits so that they are individually non-resonant to the frequency of said signal energy and intercoupling said circuits thru the anode-cathode capacitance of the relay whereby a network is formed which is resonant to said frequency.

10 In testimony whereof, we have hereunto set our hands.
